INCANDESCENT LAMP

Reginald K. Braunsdorff, East Orange, N. J., assignor to Tung-Sol Lamp Works, Inc., Newark, N. J., a corporation of Delaware

Application October 8, 1945, Serial No. 621,046

4 Claims. (Cl. 176—16)

1

This invention relates to incandescent electric lamps and particularly miniature lamps although the invention has utility in larger sized lamps.

One object of the invention is an incandescent electric lamp having a mount structure which is characterized by its durability and strength and by its efficient functioning as a getter for the lamp.

Further objects of the invention will hereinafter appear.

For a better understanding of the invention reference may be had to the accompanying drawings forming a part of this application, wherein

Fig. 1 is a perspective view of an incandescent lamp embodying the invention;

Fig. 1A is an enlarged perspective view of a part thereof; and

Fig. 2 is a perspective view of a filament mount according to another embodiment of the invention.

The invention is illustrated as being embodied in a miniature incandescent lamp embodying an envelope 4, a base 2, a press 6, a major filament 16 and a minor filament 18. The major filament 16 is carried by a pair of lead-in wires 10 and 12 with the legs of the filament welded to the upper righthand bends 24 of the support wires.

The minor filament 18 is carried by one support wire 20 in the form of an angle section welded to the support wire 10 and by a second support wire 21 in the form of an angle section which is welded to a lead-in wire 14.

The filament 16 is of conventional tungsten wire while the wire supports 10 and 12 are of different metals such, for example, as nickel. The conventional weld between the legs of the tungsten filament 16 and the support wires 10 and 12 is not truly a fusion of parts, the tungsten being merely pressed into place in the nickel lead with an overflow of nickel metal surrounding or partially surrounding the filament leg and holding the leg in position mechanically.

In the gettering of incandescent lamps and the like the gettering material such, for example, as zirconium and other getters is introduced into the envelope or bulb to function merely as a getter without functioning in any manner to increase the strength and durability of the mount itself and in accordance with this invention the getter is introduced into the bulb or envelope in the form of a solid getter metal as, for example, zirconium and in a manner to reinforce and otherwise improve the structure of the mount at the weld between the tungsten filament legs and the support wires as, for example, nickel

2

wires. The introduction of the solid getter metal has the advantage over the conventional powdered zirconium in that the solid zirconium is free from the explosive and burning character of the powder and need not be handled with the same care in the manufacture of the lamps.

In the embodiment of Figs. 1 and 1A the getter material is in the form of zirconium wire 23 incorporated in part in the welds between the legs of the filament 16 and the support wires 10 and in the embodiment shown in Fig. 1A only one of the welds is thus formed although it is understood that both of such welds may be thus constructed.

15 The embodiment consists of a slip-coil 23 placed over the leg of filament in position at the point of weld. The parts to be welded are assembled in the usual manner between conventional welding tips (omitted for convenience).

20 Welding current is controlled in the conventional manner. The use of zirconium slip-coil provides a protective layer to the filament leg and prevents crystallization of tungsten. In a conventional tungsten nickel weld a true weld is not attained,

25 the temperature reaching a value to cause the nickel to flow and embed the filament leg mechanically. By applying a getter slip-coil, as for example zirconium, over the leg the upper welding electrode rests directly in contact with the outer surface of the zirconium coil, thereby introducing a layer of zirconium metal between the upper electrode and the tungsten leg. This acts as a heat radiator. Flow of metals during the welding current is then confined to the nickel wire in contact with the top electrode. Since there is an alloying between zirconium and nickel, this establishes an excellent fused weld, in the center of which is embedded the tungsten filament leg. During the welding the leg has been well protected from excess heat, thereby eliminating any tendency to become brittle at this point. The zirconium metal welds and flows nicely, as well as the nickel below, producing an excellent fused mass of flowed metal around the point of weld. Not only may the lamp thereby be efficiently gettered but also the strength and endurance of the weld is substantially increased, with fewer imperfect welds and fewer rejections and premature filaments.

40 45 50 55 In the embodiment of Fig. 2 the solid getter metal forming a part of the weld between the filament leg and the support wire is in the form of a getter tab 22 as, for example, of solid zirconium. The zirconium tab 22 is applied over the filament leg weld to improve the strength of

weld. This is accomplished in part by protecting against the heat of welding. The zirconium metal tab flows readily at welding temperature and establishes a zirconium-nickel alloy at this point, causing the filament leg to become embedded in the center section of fused parts. The conventional tungsten nickel weld, as indicated above, is not truly an electrical fusion of parts, the tungsten being merely pressed into place in the nickel lead with an overflow of nickel metal surrounding or partly surrounding the filament leg and holding the leg in position mechanically. On subsequent burning of the filament there is the repeated expansion and contraction at this point with the result that the tungsten filament leg in the conventional weld may become loosened from its nickel base. The addition of a zirconium tab over this point prevents such loosening because the zirconium metal itself will tend to flow simultaneously with the flow of nickel and fuse into a common mass, probably a true alloying of metals, in the center of which is held and maintained the leg of filament. This provides positive mechanical holding of leg in true welded position. The introduction of the zirconium tab over the conventional parts separates the welding electrodes by this thickness of metal. Current flow is established through the joint but the tungsten filament leg does not attain the full temperature of fusion. By so protecting there is less tendency for the tungsten to become crystallized or brittle in this section. The zirconium tab acts as a radiation element and thereby protects leg of filament from excessive welding temperature.

In this embodiment also the tab or tabs 22 function both as efficient gettering means throughout the life of the lamp and as a means for strengthening and increasing the endurance of the welds and minimizing impairment of the tungsten filament legs.

While I have described solid zirconium as being the preferred gettering metal for use in the invention, it is understood that other gettering metals such, for example, as hafnium, columbium, etc. may be used with certain of the advantages above enumerated with respect to zirconium present in this structure.

This application is a continuation in part of application, Serial No. 480,438 filed March 25, 50 1943 abandoned October 11, 1945.

I claim:

1. In an incandescent electric lamp having a filament and supporting wires to which the legs of the filament are welded, means for gettering the lamp and improving and protecting at least one of the welds comprising a zirconium wire coil about the filament leg and extending beyond the weld, said coil portion in the vicinity of each weld being alloyed with the supporting wire thereby providing a substantially lower resistance weld with the coil firmly bonded thereto, said coil being heated both by its close proximity to the filament and by absorption of heat in the weld to perform gettering action during the life of the lamp and maintaining the welded area at a lower temperature with a resultant decrease in resistance by the absorption of heat therefrom.

2. In an incandescent electric lamp having a filament and supporting wires to which the legs of the filament are welded, means for gettering the lamp and improving and protecting at least one of the welds comprising a zirconium metal

5 structure surrounding the filament leg and extending beyond the weld, said structure in the vicinity of each weld being alloyed with the supporting wire thereby providing a substantially lower resistance weld with the structure firmly bonded thereto, said structure being heated both by its close proximity to the filament and by absorption of heat in the weld to perform gettering action during the life of the lamp and maintaining the welded area at a lower temperature with a resultant decrease in resistance by the absorption of heat therefrom.

10 3. In an incandescent electric lamp having a filament and nickel supporting wires to which the legs of the filament are welded, means for gettering the lamp and improving and protecting at least one of the welds comprising a zirconium structure at and extending beyond the weld, said structure and the support wire in the vicinity of the weld being fused into a common mass with the filament leg embedded therein and with the supporting wire thereby providing a substantially lower resistance weld with the structure firmly bonded thereto, said structure being heated both by its close proximity to the filament and by absorption of heat in the weld to perform gettering action during the life of the lamp and maintaining the welded area at a lower temperature with a resultant decrease in resistance by the absorption of heat therefrom.

15 4. In an incandescent electric lamp having a filament and supporting wires to which the legs of the filament are welded, means for gettering the lamp and improving and protecting at least one of the welds comprising a getter metal structure at and extending beyond the weld, said structure and the support wire in the vicinity of the weld being fused into a common mass with the filament leg embedded therein and with the supporting wire thereby providing a substantially lower resistance weld with the structure firmly bonded thereto, said structure being heated both by its close proximity to the filament and by absorption of heat in the weld to perform gettering action during the life of the lamp and maintaining the welded area at a lower temperature with a resultant decrease in resistance by the absorption of heat therefrom.
